UNITED STATES PATENT OFFICE.

PAUL SZLUKA, OF UNIONVILLE, OHIO.

LOCK.

1,012,292.

Specification of Letters Patent. Patented Dec. 19, 1911.

Application filed September 16, 1911. Serial No. 649,678.

To all whom it may concern:

Be it known that I, PAUL SZLUKA, a subject of the King of Hungary, residing at Unionville, in the county of Lake and State 5 of Ohio, have invented certain new and useful Improvements in Locks, of which the following is a specification, reference being had therein to the accompanying drawing.

This invention relates to locks, and more 10 particularly to that type commonly styled a "padlock."

The object of my invention is to provide a lock-body with a novel form of shackle that can be easily and quickly locked in a 15 closed position.

I attain the above object by a lock consisting of comparatively few parts easily and quickly assembled.

The construction of the lock is simple 20 throughout and easily locked or unlocked by a key.

The construction of the lock is such that the mechanism thereof cannot be tampered with and the lock surreptitiously opened.

25 The invention will be hereinafter specifically described and then claimed, and reference will now be had to the drawing, wherein like numerals of reference designate corresponding parts throughout the several 30 views, in which:—

Figure 1 is a side elevation of the lock in connection with a staple and hasp. Fig. 2 is a longitudinal sectional view of the lock. Fig. 3 is a cross-sectional view taken 35 on the line III—III of Fig. 2; and Fig. 4 is a similar view taken on the line IV—IV of Fig. 2.

A lock in accordance with this invention 40 comprises a cylindrical body or barrel 1 having a longitudinal central bore 2 extending from one end thereof to the opposite end. The inner end of the bore 2 is enlarged and the walls thereof screw-threaded, as at 3.

45 Adjacent to the inner end of the body 1 is a recess 4 that intersects the bore 2 of the body. The lower closed end of this recess is disposed at an angle, as at 5, to receive a flat head 6, carried by the hook-shaped end 7 of a shackle 8. The outer end 50 of the shackle is pivotally mounted between apertured lugs 9 by a pin or rivet 10. The apertured lugs 9 are carried by the side of the body 1, at the outer end thereof. The

head 6 of the shackle has an opening 11 to 55 provide clearance for a pin 12 located within the bore 2. The inner end of the pin 12 is enlarged and screw-threaded, as at 13, to screw into the threaded end of the bore 2. The inner end of the pin 12 has a shank or 60 stem 14 and adapted to be mounted over the shank or stem is the inner end of a key 15. This key has a socket 16 to receive the shank or stem 14. The shape of the recess 4 permits of the head 6 being easily swung 65 into and out of said recess. The pin 12 is placed in the bore 2 through the opening of the head 6 and is rotated until the threads of the pin engage the threads 3 of the bore 2. The pin 12 is prevented from sliding out 70 of the bore, and the key 15 can be inserted in the outer end of the bore to engage the pin 12, whereby said pin can be further rotated into the bore 2 to firmly lock the hook-shaped end of the shackle within the 75 lock-body.

The lock is illustrated in connection with a staple 17 and a hinged hasp 18. The lock occupies a very small space in connection with the staple and hasp, and the hook-shaped end of the shackle supports the lock-body in such a position that a key can be easily inserted in the same and water or other matter cannot enter the keyhole of the lock.

85 The lock in its entirety is made of light and durable metal and can be made of various sizes.

What I claim is:—

A lock comprising a cylindrical body provided with a longitudinal bore for the insertion from one end of a key, the wall of said bore provided with threads at that end opposite the end of the bore in which the key is inserted, said body further having 90 at one end a transversely extending inclined recess intersecting said bore, a shackle including a longitudinally extending portion and a hook-shaped portion having the outer part thereof extending inwardly at an inclination and enlarged, means for pivotally connecting one end of said longitudinally extending portion upon one end of said body, said enlarged part of hook-shaped portion of said shackle having an opening 95 and capable of extending in said recess and across said bore, a pin extending in said bore and having its outer portion engaging

2
said threads and projecting through said opening for securing the hook-end of the shackle in operative position, and said pin of a length as to extend in proximity to the smooth end of said bore and reduced for the reception of a tool to facilitate the positioning and removing of the pin.

In testimony whereof I affix my signature in the presence of two witnesses.

PAUL SZLUKA.
